UNITED STATES PATENT OFFICE.

HUNTER DENNIS, OF TRACY, CALIFORNIA, ASSIGNOR OF ONE-THIRD TO SAMUEL SCHMIDT, OF TRACY, CALIFORNIA.

WRITING IMPLEMENT.

1,148,661.

Specification of Letters Patent.

Patented Aug. 3, 1915.

Application filed February 13, 1915. Serial No. 8,057.

To all whom it may concern:

Be it known that I, HUNTER DENNIS, a citizen of the United States, residing at Tracy, in the county of San Joaquin and State of California, have invented certain new and useful Improvements in Writing Implements, of which the following is a specification, reference being had to the accompanying drawings.

10 This invention relates to certain improvements in writing implements; and an object of the invention is to provide a device of this general character having novel and improved means whereby the marking extremity of the implement may be illuminated.

Furthermore, it is an object of the invention to provide a device of this general character having coacting therewith novel and improved illuminating means under 20 control of an electric circuit and whereby the source of electrical energy may be carried by the implement.

The invention consists in the details of construction and in the combination and arrangement of the several parts of my improved writing implement whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view, partly in elevation and partly in section, of a writing implement 40 constructed in accordance with an embodiment of my invention, said implement being disclosed as a fountain pen; Fig. 2 is a view, partly in top plan and partly in section, of the implement as disclosed in Fig. 1; Fig. 3 is a fragmentary view, partly in elevation and partly in longitudinal section, of the implement as herein embodied; Fig. 4 is an enlarged sectional view taken substantially on the line 4—4 of Fig. 1, looking 50 in the direction of the arrow; Fig. 5 is a view, partly in elevation and partly in section, of a further embodiment of my invention, the implement being disclosed as a

pencil; Fig. 6 is a view in top plan of the device as disclosed in Fig. 5, with the shade 55 member removed; Fig. 7 is a sectional view taken substantially on the line 7—7 of Fig. 5; and Fig. 8 is a fragmentary view, enlarged, illustrating the securing means herein embodied for maintaining certain parts 60 in applied position upon the implement.

As disclosed in Figs. 1 to 4, 1 denotes the barrel of a conventional fountain pen having secured to the open extremity, in a well known manner, the stock 2 adapted to receive the point 3. Surrounding the barrel 1 in close proximity to the open end thereof is a strap 4 having secured thereto the socket 5 disposed on an incline toward said open end of the barrel and with which is 65 adapted to be engaged a conventional bulb 6, the rays whereof being directed upon the point 3 and the adjacent surface with which it may be coacting by the shade 7 operatively engaged with the strap 4 immediately adjacent the socket 5 and disposed on a curvature whereby the same overlies the bulb 6. The shade 7, as is believed to be self-evident, also affords a medium whereby the eyes of the user of the writing implement are protected against the rays of light emanating from the bulb 6.

The barrel 1 has disposed longitudinally thereof the interior bead 7 provided with a bore 8 extending through the rear of the 85 barrel 1 and extending at a point adjacent the socket 5 outwardly through the side wall of the barrel, as indicated at 9, and through which are disposed the conductors 10 in electrical connection with the socket 5 90 and with the contact members 11 at the closed end of the barrel 1.

12 denotes a slip cap of non-conductive material having its bore divided into two compartments by the septum 14, the outer 95 end of one of the compartments 15 being adapted to be closed by the head 16 removably engaged therewith. A side wall of the slip cap 12 is provided with a bore 17 through which is disposed an electrical conductor 18 in engagement with the spring contact 19 carried by the septum 14 and with a contact 20 carried by the outer end of the compartment 15, said contact 20 being adapted to engage the spring contact 21 100 carried by the removable head 16. The

spring contact 20 is adapted to engage the contact 22 at one end of the battery B and adapted to be inserted within the compartment 15 through the open end thereof, while the spring contact 19 is adapted to engage the contact 11 when the slip cap 12 is disposed over the closed end of the barrel 1, as is believed to be clearly shown in Fig. 2. The second contact 11 is adapted to engage the contact 23 disposed through the septum 14 and in suitable engagement with the battery B whereby it will be perceived that upon applying the slip cap as shown in Figs. 1 and 2, an electrical circuit will be closed for illuminating the bulb 6. It will also be seen that by having the contact 21 carried by the head 16, no obstruction will be afforded to the insertion or removal of the battery B.

In the form of invention disclosed in Figs. 5 to 8, 24 denotes a conventional pencil having detachably engage with one extremity thereof the cap 25, also of non-conductive material, the bore whereof being divided by the septum 26 to afford the compartment 27 to receive the battery B', the outer or open end of the compartment 27 being closed by the head 28 detachably engaged with the cap in a well known manner.

The writing implement 24 adjacent the marking extremity thereof is surrounded by the split band 29, the adjacent extremities whereof being provided with the coacting locking members, herein disclosed as a hasp 30, pivotally engaged with one extremity of the band and having coacting therewith the latch member 31 pivotally engaged with the opposite extremity of the band and adapted to be disposed through the hasp member 30 in a conventional way, whereby it will be perceived that the band 29 may be applied to or removed from the implement 24 with convenience and facility. The band 29 is provided with the forwardly inclined socket 32 adapted to have engaged therewith the bulb 33 and said band is also provided with the shade member 34 overlying the bulb 33, for a purpose which has been hereinbefore set forth relative to the shade member 7.

The cap 25 is provided in the side thereof with the sockets 35 in electrical connection with the opposite extremities of the battery B' through the medium of the spring contacts 36, one of said contacts being carried by the removable head 12 and adapted to coact with the conductor 37 disposed through the channel 38 formed longitudinally of the cap 25. The sockets 35 are adapted to receive the plugs 39 having secured thereto the conductors 40 adapted to be electrically engaged with the socket 32. The conductors 40 are also disposed through the eyes 41 carried by the bracket 42 mounted upon the strap 43 also disposed around the implement 24 at a predetermined point thereon. Threaded through the bracket 42

and adapted to engage the conductors 40 within the eyes 41 are the clamping screws 44 serving to maintain the portions of the conductors 40 intermediate the socket 32 and the bracket 41 taut so that no interference especially from entanglement, will be offered during the use of the implement 24. The band 43 is adapted to be clamped upon the implement 24 in the same manner as has been referred to relative to the band 29, and for this reason the hasp and its coacting latch are identified by the same reference characters as employed in connection with the band 29.

From the foregoing description it is thought to be obvious that a writing implement constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In combination with a hollow writing implement provided with a supplemental longitudinally disposed bore, an illuminating member carried by the implement exteriorly thereof, said illuminating member being positioned rearwardly of and in close proximity to its writing end, conductors leading from the illuminating member and disposed through the supplemental bore and terminating in contacts, a slip cap of non-conductive material engageable with either extremity of the writing implement, a source of electrical energy carried thereby, and contacts carried by the slip cap in electrical connection with the source of energy and adapted to engage the contacts of the writing implement when the slip cap is in applied position on the extremity of the implement remote from the writing point thereof.

2. In combination with a writing implement, an illuminating member carried thereby exteriorly thereof, said illuminating member being positioned rearwardly of and in close proximity to the writing point of the implement, conductors in electrical connection with the illuminating member and disposed longitudinally of the writing implement and terminating in contacts, a cap of non-conductive material and having an open end to removably receive an extremity of the writing implement, a source of electrical supply carried by the cap, and contacts carried by the cap inwardly of its open

end in electrical connection with the source of supply, the contacts of the writing implement and the contacts of the cap being capable of engagement when the cap is in applied position on the extremity of the implement remote from the writing point thereof.

In testimony whereof I hereunto affix my signature in the presence of two witnesses.

HUNTER DENNIS.
